UNITED STATES PATENT-OFFICE.

JOHN W. NOWAK, OF ALLEGHENY, PENNSYLVANIA.

PROPELLER-WHEEL.

SPECIFICATION forming part of Letters Patent No. 729,397, dated May 26, 1903.

Application filed February 9, 1903. Serial No. 142,551. (No model.)

To all whom it may concern:

Be it known that I, JOHN W. NOWAK, a citizen of the United States of America, residing at Allegheny, in the county of Allegheny and State of Pennsylvania, have invented certain new and useful Improvements in Propeller-Wheels, of which the following is a specification, reference being had therein to the accompanying drawings.

10 This invention relates to certain new and useful improvements in propeller-wheels such as are generally employed in connection with boats of the "stern-wheel" type and those of the "side-wheel" type.

15 The object of the invention is to construct a propeller-wheel with the propeller-blades so arranged that they will pass into the water without offering any resistance, then be brought to the proper propelling position, 20 and as they reach the end of their propelling-stroke will be tilted, whereby to lift out of the water without raising any water therewith, thus materially increasing the effectiveness of the propeller-wheel, owing to the fact that 25 no power is required to force the blades into the water or lift the same out of the water, as is the case in propeller-wheels where the blades are rigidly mounted at their ends in the carriers therefor.

30 Still further objects of my invention reside in the novel means for giving the desired inclinations to the blades, and in the case of boats of the stern-wheel type to provide a fender for the wheel pivotally hung, whereby 35 to be raised out of the way above the wheel when not desired for use, and when desired to be lowered, so as to guard the wheel from floating debris.

With the above and other objects in view 40 the invention consists in the novel construction, combination, and arrangement of parts to be hereinafter more specifically described and then particularly pointed out in the appended claims, and in describing the invention 45 in detail reference will be had to the accompanying drawings, forming a part of this application, and wherein like numerals of reference will be employed for indicating like parts throughout the several views, in which 50 drawings—

Figure 1 is a detail perspective view of my improved propeller-wheel as applied to a ves-

sel of the stern-wheel type, showing the dashboard of the vessel and the fender in its lowered position. Fig. 2 is an elevation of the 55 propeller-wheel. Fig. 3 is a diagrammatical detail view of the wheel. Fig. 4 is an end view thereof. Fig. 4^a is a central vertical section of Fig. 4. Fig. 5 is a detail side elevation of a modified form of blade or paddle. 60 Fig. 6 is a detached detail side elevation of the preferred form of supporting wheel or spider for the blades or paddles. Fig. 7 is an end view showing a modified form of driving means. Fig. 8 is a like view of another 65 form of modified construction.

The blades or paddles are rotatably mounted in the ends of the wheel and are provided on each end with a crank connected to eccentrics operated by the driving-shaft of the 70 wheel, whereby these blades or paddles are always vertical during the revolution of the wheel, thus permitting their entry into the water with practically no resistance, also presenting their full width to the water during 75 the portion of the travel of the wheel when the blades are in the water in propelling position and their lifting out of the water without lifting of the water.

In the illustration of my invention I have 80 shown the same applied to the stern type of vessel, though it is applicable alike to vessels of the side-wheel type. To put the invention into practice with a vessel of the stern-wheel type, I employ a drive-shaft 1, which is 85 mounted in suitable bearings on the supporting-beams 2. The drive-shaft carries cranks 3, to which the pitman or driving rods 4 are connected, these pitman or driving rods working through an opening 5 in the dashboard 6. 90 The wheel embodies disks 7, concentrically mounted on the shaft 1, near each end thereof, these disks being provided with annular outwardly-extending flanges 8, over which the cap-plates 9 are placed and suitably secured, thus inclosing the driving mechanism 95 from the action of or exposure to the water. The blades or paddles 10 are provided with journals or spindles 11 on their ends, which are mounted in the concentric disks 7. These 100 blades or paddles are provided with beveled edges, whereby to cause the same to enter the water with the least possible resistance and also lift out of the same with the least possi-

ble resistance and also without lifting any water therewith. I may provide but one central or intermediate support for the blades or paddles or I may provide a plurality of intermediate supports.

Fig. 2 shows the wheel constructed with a single supporting wheel or spider for the blades, the preferred form of construction of which is shown in detail in Fig. 6. This wheel 12 is concentrically mounted on the shaft 1, centrally thereof, and is provided on its rim or periphery with bearings 14 to receive the central or intermediate spindles or journals 15, formed in the paddles or blades.

A modified form of construction for the paddles or blades is shown in Fig. 5, in which each paddle or blade comprises the journals 16, having crank ends 17. The journals 16 are mounted in the disks 7, and the paddle or blade comprises a series of sections 18, connected together by journals or spindles 19, having clamp ends 20 riveted to the sections 18. Where a blade or paddle of this form of construction is employed, I will of course employ a series of the supporting wheels or spiders 12 on the drive-shaft 1.

With the form of blades or paddles shown in Figs. 1, 2, and 4 I connect a crank 21 to each of the spindles 11. These cranks carry wrist-pins 22, which engage in a disk 23, loosely mounted on the eccentric 25 and provided with a flange 24, which is mounted on a stationary eccentric 25, provided with a sleeve 26, in which the shaft 1 turns, which sleeve is rigidly supported from the bearing for the shaft. As the wheel as an entirety is revolved, it will be noted that the disk 23 being rotated rotates the paddles or blades, so as to maintain the same vertical at all times, whereby they enter the water edge-wise, be presented broadside while traveling rearward through the water, and elevated edge-wise out of the water. It is to be noted that by this means a wheel of much less diameter may be employed than where the paddles or blades are presented sidewise to the water as they enter the same and also as they are being lifted out of the water, permitting the revolution of the wheel at a much greater rate of speed, and consequently obtaining a higher rate of speed for the vessel with the same or less power expended.

In order to protect the wheel from floating debris in the water, especially where applied to vessels of the stern-wheel type, I may employ a fender 27, standing out some distance from the wheel at the center and tapering toward each end of the wheel, whereby any floating object striking the fender will be projected to one side or the other of the vessel. This fender, for the sake of lightness, is preferably of skeleton or lattice-work form, comprising the horizontal frame-bars and the vertical or upright bars 28. The frame of the fender is supported by brackets 29, which are loosely mounted on the drive-shaft 1, stops

30 and 31 being provided for limiting the upward and downward movement of the fender, respectively. The fender is conveniently operated by means of a chain or other connection 32, attached to a central bar 33 and passing through the dashboard 6, where it may be secured at any suitable point. The stop 31 forms a rest for the fender when the same is in the lowered position, thus supporting the same at both ends, as well as the same being supported at the center by the chain 32.

In Fig. 7 I show a modified form of driving means in which I employ gears in lieu of the cranks on the ends of the blades or paddles and intermediate gears for driving the same. To this end I mount on the spindles or journals of the blades gears 34, which mesh with smaller gears 35, loosely mounted on the disks 7. Motion is imparted to these gears through the medium of a stationary gear 36 (acting the same as the stationary cam 25) and engaging gears 37, also loosely mounted on the disks 7.

In Fig. 8 I also show another modified form of driving means for the blades or paddles in which I employ sprocket-wheels 38, mounted on the spindles or journals of the blades or paddles operated by a chain 39, operating over said wheels and over a stationary sprocket-wheel 40. Driving means of either of these forms accomplish the same result in the actuating of the blades or paddles, and the cap piece or plate 9 protects the driving mechanism from exposure to the water.

Having fully described my invention, what I claim as new, and desire to secure by Letters Patent, is—

1. A device of the character described, comprising in combination with a drive-shaft, disks mounted thereon, blades or paddles journaled therein, stationary eccentrics carried by the shaft-bearings, loosely-mounted disks carried by said eccentrics and connected with said paddles, and means for closing the first-named disks to inclose said eccentrics and loosely-mounted disks, substantially as described.

2. A device of the type set forth comprising a drive-shaft, bearings therefor, disks concentrically mounted on the shaft, annular outwardly-extending flanges formed on said disks, cap-plates secured on said flanges to close said disks, blades journaled in said disks, cranks secured to the blades, stationary eccentrics carried by the shaft-bearings, and loosely-mounted disks carried by the eccentrics and connected to the cranks of said blades, whereby the paddles are held in a vertical position, substantially as described.

In testimony whereof I affix my signature in the presence of two witnesses.

JOHN W. NOWAK.
